DITCHER DRIVING AND STEERING
MECHANISM

Harry A. Barber, Leonard S. Burns, and Edward J. Roots,
Aurora, Ill., assignors to Barber Greene Company,
Aurora, Ill., a corporation of Illinois
Continuation of application Ser. No. 635,632, Jan. 23,
1957. This application Mar. 25, 1960, Ser. No. 17,650
5 Claims. (Cl. 37—97)

This invention relates generally to a ditch digging machine. More particularly, this invention relates to a ditch digging machine generally of the type including a self-propelled vehicle or tractor having a digging trench conveyor extending transversely of the digging wheel for unloading the material dumped from the digging wheel upon the conveyor.

This application is a continuation of our application Serial No. 635,632, filed January 23, 1957, now abandoned.

The present invention concerns itself with the provision of means for solving several of the outstanding problems faced by manufacturers in the manufacture of a more efficient trench digger and one which has increased utility.

To this end, there is herein provided new and improved means for transmitting the power from the power source or engine to the digging mechanism in the form of a drive shaft paralleling mechanism. The instant mechanism is adapted to compensate for irregular movements and varying trenching depths. The mechanism aids in the provision of a digging machine which has the ability to cope with slopes, fills, stumps, stones, and still dig a fairly straight and level trench. Also, by virtue of the present invention, the need for the conventional type of sprocket chain drive has been eliminated which has not been satisfactory since in operation the chain has a tendency to jump the sprocket thus interfering with the operation of the digging machine and causing time delays.

In addition to the foregoing, new means has been evolved to reduce the stress between the tractor and the digging wheel assembly when the ditcher is digging along a curve.

Accordingly, an object of this invention is to provide a new and improved ditcher which may dig along a curve with a minimum amount of stress between the digger wheel and the trench.

Another object of this invention is to provide new and improved drive means for transferring power from the power source on a ditcher to a digging wheel carried by the ditcher and eliminating the undesirable conventional jack knife type of chain drive heretofore used for transmitting power to the digging wheel.

A still further object of the invention is to provide a simplified and improved draft structure accommodating the digging of a ditch along a curve by taking the draw bar pull between the tractor and digging wheel assembly along the outer side of the tractor and digging wheel assembly when the tractor is turning, to draw the digging wheel assembly to dig a curve in either direction and by equally distributing the draw bar pull between each side of the tractor and the digging wheel assembly when the tractor is traveling in a straight ahead direction.

These and other objects of the invention will appear from time to time as the following specification proceeds and with reference to the accompanying drawings wherein:

FIGURE 1 is a view in side elevation of a ditching machine constructed in accordance with the present invention;

FIGURE 2 is a fragmentary plan view of the rear end

2

portion of the ditching machine with certain parts broken away and certain other parts shown in horizontal section in order to illustrate certain details of the draft connection from the tractor to the digging wheel structure;

FIGURE 3 is an enlarged fragmentary detail view in side elevation, illustrating certain details of the drive to the digging wheel structure and certain details of the draft connection to the digging wheel structure and elevating means therefor;

FIGURE 4 is an enlarged fragmentary sectional view taken substantially along line IV—IV of FIGURE 3;

FIGURE 5 is a fragmentary view in side elevation of the ditching machine drawn to a smaller scale than FIGURE 3, and illustrating the mechanism for raising and lowering the digging wheel structure;

FIGURE 6 is a partial fragmentary plan view of the machine illustrating the mechanism for raising and lowering the digging wheel structure;

FIGURE 7 is a partial fragmentary rear end view looking toward the rear end of the tractor and showing the differential for driving the digging wheel structure and the connectors for supporting the differential and connecting the digging wheel assembly to the tractor; and

FIGURE 8 is an enlarged fragmentary partial horizontal sectional view taken through the motion limiting connection accommodating the draw bar pull to be taken on either connector depending upon the direction the tractor is turning to draw the ditcher around the curve.

In the embodiment of the invention illustrated in the drawings, a wheel type trench digging machine is shown in FIGURE 1 as including a self-propelled vehicle in the general form of a tractor 10. The tractor 10 includes generally a box-like frame structure 12 having parallel spaced side frame members 44 connected together at their rear ends by a transverse I-beam 46. The frame structure 12 is supported on suitable traction devices, herein shown as being continuous traction tread devices in the form of crawlers 11. The tractor 10 carries the power mechanism for driving the crawlers 11, as well as a digging wheel 14 and serves as a propulsion device to draw the digging wheel 14 to dig a trench in the ground, as will hereinafter more clearly appear as this specification proceeds.

The frame structure 12 includes a pair of laterally spaced vertically extending supports 15, shown as being in the form of channels and extending vertically from the rear end portions of the side frame members 44 of the frame structure and suitably braced to the frame structure 12. The upper ends of the vertically extending supports 15 have sheaves 34 and 43 mounted thereon over which are trained flexible cables 33 and 39 respectively, for elevating or lowering and tilting the digging wheel 14 with respect to the frame structure 12, and for retaining the digging wheel in a desired position of adjustment with respect to the ground, as will hereinafter more clearly appear as this specification proceeds.

Transversely pivoted to each of the supports 15 adjacent the upper ends thereof, but beneath the sheaves 34 and 43 on pivot pins 16 are vertically extending guide members 17 shown as being in the form of I-beams and depending from the pivot pins 16 and mounted thereon for angular movement toward and from the frame structure 12. The laterally spaced vertical supports 15 and guide members 17 form mast structures over which the flexible cables 33 and 39 are trained to support spaced arms 23 of a boom structure 22, supporting the digging wheel 14 and connecting the digging wheel 14 to the frame structure 12, to be pulled by the tractor 10 during the digging operation. The arms 23 of the boom structure 22 have spaced upward extensions 24 extending along opposite sides of the connectors 18 (FIGURE 8). The connectors 18 are herein shown as being in the form of

plates extending rearwardly of the guide members 17 and guided for slidable movement along said guide members. Pivot pins 25 serve to connect the upward extensions 24 to the connectors 18. The connectors 18 and guide member 17 thus form connectors for the boom structure 22, connecting the boom structure to the frame structure 12 for vertical movement with respect to said frame structure and for independent limited movement toward and from said frame structure.

Each connector 18, as shown in FIGURES 4 and 5, is slidably connected to the associated guide member 17 by means of guide brackets 19 secured to the upper and lower end portions of said connector, as by bolts 20 extending through said brackets and connector. The guide brackets 19 have forwardly opening gibbed guides 21, the gibs of which slidably extend along the inside of a rear flange 17a of the I-beam forming the guide member 17, and thereby retain the associated connector for vertical movement along said guide member.

The digging wheel 14 is of a generally ring-like form suitably mounted between the arms 23 of the boom structure 22 and having digger buckets 13 projecting from the periphery thereof.

The connectors 18, boom structure 22 and digging wheel 14 are elevated and lowered and are retained in the desired position of adjustment by the flexible cables 33 and 39 operated by hydraulic cylinders 26 and 27 respectively. The hydraulic cylinder 26 is pivotally connected between the vertical supports 15 and extends forwardly therefrom and has a piston rod 28 extensible therefrom having a transverse shaft 29 mounted on its forward end and extending from opposite sides thereof. Sheaves 30 are rotatably mounted on opposite ends of the shaft 29. The flexible cables 33 are connected to fixed connectors 32'-32" on upright frame members 32a extending upwardly from the frame structure 12. Each cable is trained rearwardly from its connector 32a around the sheave 30 and forwardly therefrom to and around a sheave 31 mounted on the upright frame member 32a on a support bracket 32 disposed beneath the connector 32'. From the sheave 31, the flexible cable 33 extends over and around the sheave 34 downwardly to the connector 18 and is connected to an ear 18a, extending outwardly from said connector, on an adjustable clevis and bolt mechanism 35 (FIGURES 3 and 5). The admission of fluid under pressure to the piston rod end of the cylinder 26 under the control of suitable valve means (not shown) will thus retractably move the piston rod 28 and sheaves 30 and vertically move the connectors 18 and boom structure 22 with respect to the ground. Upon the release of fluid under pressure from the piston rod end of the cylinder 26, the connectors 18 and boom structure 22 may be lowered by gravity. The holding of fluid under pressure in the piston rod end of the cylinder 26 will retain the connectors 18 and boom structure 22 in the desired position of adjustment with respect to the ground.

The cylinder 27 is suitably connected between the vertical supports 15 at its rear end and extends forwardly therefrom and has a piston rod 36 extensibly and retractably movable with respect thereto. The piston rod 36 has a transverse shaft 37 mounted at its forward end and extending from opposite sides thereof and having sheaves 38 mounted on each end thereof. The flexible cables 39 extend from connectors 40 mounted between the upright frame members 32a and forwardly therefrom to and around the sheaves 38. From thence, the flexible cables 39 extend forwardly to and around sheaves 42 suitably mounted between the vertical frame members 32a. The flexible cables 39 then are trained over the sheaves 43 mounted on the mast structure formed by the vertical support 15 and rearwardly and angularly downwardly therefrom to upright connecting means 41 at the rear end portion of the boom structure 22 adjacent opposite sides thereof.

The hydraulic cylinder 27 may thus angularly move the boom structure 22 about the axes of the pivot pins 25

5 to tilt the boom structure with respect to the ground and to maintain the boom structure in the desired angular relation with respect to the ground for digging or for traveling from the working place to working place.

A means is provided to limit outward movement of the connectors 18 with respect to the frame structure 12 and to accommodate the draw bar pull to be taken on either connector and to be relieved from the opposite connector when the tractor 10 is drawing the digging wheel around a curve, depending upon the direction the tractor is turning. While this means may be of various forms, as herein shown, extension plates 53 extend forwardly from the lower end portions of the guide members 17. Each extension plate 53 has a longitudinally extending slot 55 formed therein and extends between parallel spaced arms 48 and 49 of a yoke 47 secured to and extending rearwardly from the transverse beam 46. Movement of the connectors 18 toward and from the frame structure 12 is limited by stop means comprising pins 51 mounted in the arms 48 and 49 of the yokes 47 and extending through the slots 55 in the plates 53.

When the tractor 10 is traveling in a straight line direction, the connectors 18 will both be in outwardly extending relation with respect to the frame structure 12. 20 The pins 51 engaging the forward ends of the slots 55 will thus limit outward movement of the connectors 18 and the draw bar pull will be taken equally on each connector.

When the tractor 10 turns either to the right or to the 25 left to draw the digging wheel 14 to dig along a curve, the connector 18 on the inside may move toward the frame structure 12, while the connector 18 on the outside will remain in its outwardly extended position with respect to the frame structure 12 and take the entire draw bar pull. Thus, the digging wheel 14 when digging along a 30 curve is drawn with a pulling force generally pulling the digging wheel tangentially of the curve along the outer side thereof, with a resultant reduction in twisting stresses on the boom structure and the supporting and drive mechanism for the digging wheel.

It should here be understood that in a ditching machine of the class described, that in order to attain the proper balance and performance of the machine, the tractor is usually much longer than the digging wheel and its supporting boom structure forming the excavating unit. The 35 diameter of the digging wheel is usually such that when the digging wheel has dug into the ground and is below the top of the ground and is digging a ditch along the ground, that with the ditching machines heretofore in use, any effort to turn the digging wheel from a straight line 40 to dig along a curve puts undue twisting stresses on the boom structure supporting the digging wheel as well as on the tractor, and draws the digging wheel angularly with respect to the ditch, with the result that it binds and 45 frequently becomes hung up in the ditch.

In the draft structure of the present invention, the connectors 18 accommodate relative movement of the tractor 10 with respect to the boom structure 22 in horizontal directions and also may freely move vertically along the 50 guide members when the tractor is traveling along irregular terrain, and thereby reduce vertical and horizontal twisting stresses on the boom structure and digging wheel as well as on the tractor, during the digging operation.

The digging wheel 14, as shown in FIGURE 1, is driven 55 from a power unit 61 at the front of the frame structure 12. The power unit 61 may be an internal combustion engine and is selectively connected with the digging wheel and crawlers 11 through a conventional clutch assembly (not shown) in a clutch housing 62. The power unit 61 60 drives a conventional transmission contained within a transmission housing 63 under the control of a clutch in the clutch housing 62 and disposed immediately rearwardly of the clutch housing. The transmission has driving connection with a suitable geared reduction train (not shown) disposed in an auxiliary gear box 64 housing a

reduction gear train for driving a drive shaft 65 projecting rearwardly of the auxiliary gear box 64 and for driving a drive shaft 66 projecting forwardly of said gear box. The drive shaft 65 serves to drive the digging wheel 14, while the drive shaft 66 serves to drive the crawlers 11 in a conventional manner, to propel the tractor and draw the digging wheel to dig a ditch in the ground.

The drive shaft 65 has a universal joint 67 of a conventional construction connected to and driven from its rear end. The universal joint 67 drives a universal joint 69 vertically movable with the connectors 18, through a telescopic shaft 68. The telescopic shaft 68 includes a shaft 70 connected to and driven from the universal joint 67 and a tubular shaft 72 telescopically mounted on the shaft 70 and having driving connection at its free end with the universal joint 69.

The universal joint 69 has driving connection with a driven shaft 73, which shaft is shown as extending forwardly from a differential housing 74, for driving differential gearing (not shown) contained within said differential housing. Driven shafts 75 and 76 extend from opposite ends of the differential housing and are driven from the differential gearing therein.

The differential housing and differential contained therein may be a conventional differential unit, such as is used in automotive vehicles and the like. The differential housing 74 extends through and is suitably mounted adjacent its opposite ends in the connectors 18, for vertical movement therewith. As shown in FIGURE 7, the connectors 18 have parallel spaced plates 83 and 84, extending inwardly therefrom between which extend lugs 85 extending from the differential housing. The lugs 85 are spaced from the plates 83 and 84 a distance sufficient to accommodate angular movement of the differential housing with respect to the connectors 18 upon angular movement of said connectors toward and from the tractor.

The respective drive shafts 75 and 76 have sprockets 77 and 78 mounted on the ends thereof, which respectively drive sprockets 79 and 80 through individual endless drive chains 81. The sprockets 79 and 80 drive coaxial gears (not shown) which mesh with internal teeth 81 on the rims of the digging wheel 14, to drive said digging wheel and the buckets 13 to effect a ditching operation and discharge the loose material excavated onto a conventional cross conveyor assembly 82 extending through and to opposite sides of the digging wheel, as shown in FIGURE 2. The cross conveyor assembly 82 is supported on the boom structure 22 for delivering the loose excavated material to one side of the ditch or trench being excavated.

It will here be noted that the drive shafts 65 and 73 are maintained in substantially parallel relation with respect to each other throughout the range of adjustable movement of the connectors 18 and differential housing 14 with respect to the ground. This results in a more uniform drive between the shafts 65 and 73 with a resultant reduction in vibration in the drive between the two shafts. The telescopic drive connection also makes it possible to drive the digging wheel 14 in all positions of elevation of the digging wheel with respect to the ground without the use of the usual jack knife chain drives heretofore used.

It may also be seen that the drive and draft connection of the invention makes it possible for the relatively large diameter digging wheel 14 to be drawn by the tractor 10 to dig a ditch along a curve by drawing the digging wheel by the outer connector 18 and accommodating the inner connector 18 to be relatively free.

While we have herein shown and described one form in which our invention may be embodied, it will be understood that various modifications and variations in the invention may be effected without departing from the spirit and scope of the novel concepts of the invention.

We claim as our invention:

1. In a ditching machine, a self-propelled vehicle in-

cluding a frame structure having parallel spaced side frame members having transversely spaced upright supports extending upwardly therefrom at the rear end thereof, a boom structure extending rearwardly of said upright supports and having a digging wheel rotatably supported thereon, means connecting said boom structure to said upright supports to be drawn by the vehicle to effect a ditching operation comprising an individual connector associated with each upright support, said connectors being mounted for pivotal movement about horizontal transverse axes spaced above said side frame members, means pivotally connecting said boom structure to said connectors for movement about horizontal transverse axes adjacent the lower end portions of said connectors, and motion limiting means associated with each connector beneath the horizontal transverse pivotal axis thereof and accommodating independent angular movement of said connectors toward and from said upright supports and having spaced stop surfaces limiting movement of said connectors toward and from said supports, whereby the draw bar pull of the vehicle is taken through both of said connectors in a straight forward travel of the vehicle and is taken through the outer of said connectors on the outside of a curve, with the draw bar pull on the inner of said connectors on the inside of a curve being relieved when drawing the digging wheel structure to dig along a curve, and thereby minimizing angular stresses on the digging wheel and boom structure during digging along a curve and facilitating the continuous digging of ditches as the machine is turned to the right or the left.

2. In a ditching machine, a self-propelled vehicle including a frame structure having parallel spaced side frame members extending therealong, a power source carried by said frame structure and having a drive shaft, said frame structure having transversely spaced upright supports extending upwardly from said side frame members at the rear ends thereof, a boom structure extending rearwardly from said frame structure, a digging wheel supported by said boom structure, draw bar means connecting said boom structure to said upright supports comprising individual connectors associated with said upright supports and mounted for pivotal movement about horizontal transverse axes spaced above said side frame members, power transmission means connected between said drive shaft and said digging wheel for driving said digging wheel, said power transmission means including a differential supported by said connectors intermediate the ends thereof and an extensible drive connection from said drive shaft to said differential, laterally spaced drive trains driven by said differential and having driving connection with said digging wheel, means pivotally connecting said boom structure to said connectors for movement about horizontal transverse axes disposed adjacent the lower ends of said connectors, and motion limiting means associated with each connector and limiting angular movement of said connectors toward and from said upright supports in vertical planes, said motion limiting means having spaced stop surfaces limiting angular movement of said connectors toward and from said supports, whereby the draw bar pull of the vehicle is directed through both of said connectors in a straight forward travel of the vehicle and is directed through the outer connector on the outside of the curve and is relieved from the inner connector on the inside of the curve when drawing the digging wheel structure to dig along a curve, and thereby minimizing angular stresses on the boom structure and the digging wheel during digging along a curve and facilitating the digging of ditches along a curve as the machine is turned to the right or to the left.

3. In a ditching machine, a self-propelled vehicle including a frame structure, a power source carried by said frame structure and having a drive shaft extending longitudinally of said frame structure, said frame structure having parallel spaced side frame members extending longitudinally

thereof and having upright supports extending upwardly from said side frame members, a boom structure extending rearwardly from said side frame members and spaced therefrom, a digging wheel rotatably supported by said boom structure, means connecting said boom structure to said upright supports to be drawn by the vehicle to effect a ditching operation including individual connectors associated with said upright supports, means mounting said connectors for pivotal movement with respect to said upright supports about horizontal transverse axes spaced above said side frame members, horizontal transversely extending pivot pins pivotally connecting said boom structure to said connectors beneath the axes of pivotal movement of said connectors, flexible draft means trained over said upright supports and having connection with said boom structure for elevating said boom structure and digging wheel about the axes of connection of said boom structure to said connectors, other flexible draft means trained over said upright supports and having connection with said connectors for elevating said connectors with respect to said upright supports, power transmission means connected between said longitudinally extending drive shaft and said digging wheel for driving said digging wheel including a differential having a housing supported on said connectors, the support between said connectors and said housing accommodating relative movement of said connectors with respect to each other, laterally spaced drive trains driven by said differential and having driving connection with said digging wheel, and motion limiting means associated with each connector and limiting angular movement of said connectors toward and from said upright supports, said motion limiting means having two longitudinally spaced stop surfaces limiting motion of said connectors toward and from said supports whereby the draw bar pull of the vehicle to said boom structure is directed through both of said connectors in the straight forward travel of the machine and acts on the outer connector on the outside of a curve, and the draw bar pull on the inner connector on the inside of the curve is relieved when drawing the digging wheel to dig along a 40 curve.

4. In a ditching machine, a self-propelled tractor having

a frame structure having parallel spaced side frame members extending therealong, laterally spaced upright supports extending vertically from said side frame members, guide members pivotally mounted on said supports adjacent the upper ends thereof for movement about coaxial transverse axes and depending from said transverse axes, connectors guided for movement along said guide members, a boom structure transversely pivotally connected to said connectors, a digging wheel structure carried by said boom structure, said tractor having lift mechanism mounted thereon and including flexible cables trained over said upright supports and having connection with said connectors for vertically moving said connectors along said guide members, and stop means associated with each connector and limiting outward movement of said connectors with respect to said side frame members and thereby accommodating the pulling force of the tractor to be concentrated on both connectors in the straight forward travel of the tractor and to act only through the connector at the outside of a curve when turning the tractor in one direction or another so as to minimize the twisting stresses on said boom structure and said digging wheel when said tractor is drawing said boom structure and digging wheel to dig around the corner.

5. A ditching machine in accordance with claim 4, wherein the stop means limiting outward movement of the connectors with respect to the frame structure comprises individual pin and slot connections between said guide members and said frame structure.
